SOLDIER'S PARADE GAME

Filed March 5, 1930

2 Sheets-Sheet 2

UNITED STATES PATENT OFFICE

CARL A. DIEDERICH, OF HOMWOOD, PITTSBURGH, PENNSYLVANIA

SOLDIERS PARADE GAME

Application filed March 5, 1930. Serial No. 433,361.

The object of my invention is to provide belt 20 which also travels over a like roller or spool 21 removably mounted on a reduced portion of the shaft 8, as shown in Fig. 4. The endless belt 20 carries spaced L-shaped metal plates 22 which are each provided with an opening 23 to receive the stub shaft 24 depending from the play block 25 on which the mannequin figure 26 is carried. This play block 25 rides on the surface of the table 5 and tray 2, as shown in Figs. 1 and 2, and is provided with a web 27 that connects it with the under plate 28 from which the stub shaft 24 depends downwardly, as shown in Fig. 2. It will be noted that the portion of the plate 28 under the table top 5 is narrower than the portion under the tray 2 to prevent possible interference with the endless belt 20.

I attain these and other objects of my invention by the game apparatus illustrated in the accompanying drawings, in which,—
Figure 1 is a perspective view of my invention;

Fig. 2 is a detailed sectional view on line 2—2 of Fig. 1;

Fig. 3 is a top plan view of my invention with a portion broken away to show the interior construction;

Fig. 4 is a central longitudinal section substantially on line 4—4 of Fig. 3; and

Fig. 5 is a detail perspective view of one method of fastening the soldier mannequin figure to the play block.

Like numbers designate like parts in each of the several views.

Referring to the accompanying drawings, I provide a box 1 having a tray 2, the tray 2 having a portion of its rim 3 extending downwardly to engage over the upper portion of the box at 6, as shown in Fig. 4. I provide an elongated or approximately elliptical slot between the tray top 2 and the affixed central table member 5 which is permanently secured to the box by the vertical shafts 8, 9 and 10. The shafts 8 and 9 have threaded ends 7 which project above the surface of the central table member 5 and on which the base 11 of a stationary mannequin figure 12 is removably mounted.

I provide a horizontally disposed gear 14, which preferably is a beveled gear, and which meshes with the vertically disposed gear 15, which latter gear is affixed to the crank 16, the handle 17 of which functions as a means for operating the toy. The shaft 10 on which the gear 14 is keyed also carries a roller or spool 18 on which is mounted the

I provide a slot 29 preferably in the central portion of the tray 2, as shown in Fig. 1, to receive a removable strip 30 which is releasably held in place by a suitable screw 31, which may, if desired, be provided with a knurled head projecting beyond the surface of the rim 3 of the tray to permit the child to manually remove the screw and the strip 30, to permit of insertion of the play block 25 carrying the mannequin figures of United States soldiers 26. A suitable number of these play blocks carrying the mannequin soldiers is provided to permit of operatively connecting one with each of the series of spaced L-shaped perforated strips 22 carried by the endless belt.

In operation the screw 31 is removed, permitting of withdrawing the strip 30 from the tray 2 and insertion successively of the play blocks 25, the webs of which project through the slot 4 so that the bottom plates 28 prevent overturning of the mannequin figures and stub shafts 24 are inserted through the openings 23 in the plates 22, which plates are affixed in spaced relation to the endless belt 20. The endless belt which is mounted on the spools 18 and 21 is kept moving in any suitable manner as by the child grasping the handle 17 of the crank 16 which crank carries the bevel gear 15, which gear meshes with the corresponding bevel gear 14, the latter gear being keyed

or otherwise suitably affixed to the shaft 10 to which shaft the screw 18 is also affixed and thus operates the endless belt.

It will be especially noted that I require only two gears for the operation of this device; that the central table top is fixed and not removable; and that the tray 2, which is removable, has a rim 3 which seats snugly on the top of the box 1 to hold it in place. It will also be noted that the screw 31, which is provided with a roller may be readily removed and replaced to release or secure the removable strip 30 in place to which the play blocks 25 with their mannequin figures 26 are inserted to engage in the actuating plates carried by the endless belt. It will thus be seen that the child himself may put the figures in place and operate the device entirely without the assistance of an older person. Screw 31 may be any suitable screw, such as a knurled screw, as shown.

The arrangement of the tray with the rim 3 projecting downwardly over the top of the box also facilitates properly placing the top in place on the box, while the central table top 5 is substantially held in place on the box so that it cannot be readily removed.

The web 27 between block 25 and plate 28 is rounded near its side edges to permit its following a rounded course in slot 29.

Referring to Fig. 5 of the drawings, one method which I have devised of fastening the mannequin soldier figure 26 to the play block 25 is to provide a metal plate 32 having a suitable aperture 34 to receive the tack 35 by which the plate may be fastened to the play block 25. Plate 32 is provided with diagonally disposed tabs 33 which may be folded over, as shown in Figs. 1 and 2, to engage the flat base of the mannequin soldier. The tabs 33 being of flexible material permit the child to readily remove and replace any of the mannequin figures by raising these tabs sufficiently to disengage them from the base 36 of the mannequin figure and withdraw it and substitute a different figure. This makes it unnecessary to withdraw the block 30 from the tray top 2 and provides a convenient means for changing the mannequin figures used in the game.

If desired, I may provide more than one aperture 34 and also more than one tack 35 to fasten the plate to the play block and may, if desired, insert the tacks 35 directly through the base plate 36 of the mannequin figure.

An important result obtained by the combination and arrangement of parts disclosed is that the number of parts is reduced to the minimum and the cost of manufacture is thereby kept down; which, from a practical standpoint, is very important to the manufacturer.

What I claim is:

1. In a game of the class described, the

combination of a box, a removable tray on the box, said tray having its rim projecting downwardly over the upper edges of the box, a central table top held stationary on the box and having its upper surface aligned with the tray, the device having an elongated slot between the table top and the tray, a playblock having a depending member slidable in the slot, said playblock having flexible tabs diagonally mounted on the playblock, and the mannequin figures detachably engagable on the playblock by means of said flexible tabs, whereby to permit of readily attaching or removing any of the mannequin figures from the playblock. 80

2. In an amusement device of the class described, the combination of a box having a removable tray, a non-removable central table aligned with the tray, a continuous slot formed therebetween, playblocks adapted to travel in said slot, each play block having a depending stub shaft, a belt having spaced apertured plates adapted to receive the respective depending stub shafts, rollers on which the belt is mounted, and manually actuated means for turning one of the rollers, the playblocks comprising a mannequin figure, a base on which the mannequin figure is mounted, and a ribbed extension depending below said base, the playblock having flexible tabs adapted to detachably engage the base member of the mannequin figures to permit of readily detaching or replacing any desired mannequin figure from the playblock. 100
